MERCURY ARC CONVERTER

Henry Thomas Ramsay, Pinner, England, assignor to The General Electric Company Limited, London, England

Application May 23, 1939, Serial No. 275,204
In Great Britain May 26, 1938

10 Claims. (Cl. 175—354)

This invention relates to mercury arc converters of the type having liquid cathodes and wherein means are provided whereby the point in each cycle of the A. C. input at which the arc starts can be controlled by an electrical signal which induces the formation of a cathode spot. The said liquid will be termed hereinafter mercury; but it is to be understood that mercury may also be replaced by its known substitutes, e. g. 5 various amalgams.

The object of my invention is to provide converters of this type having improved said means, the main improvement being in durability and certainty of operation.

15 According to my invention a converter of the type specified comprises means for causing a stream of mercury to issue from an orifice within the envelope of the converter, normally as a continuous jet impinging on an electrode, and 20 comprises or is adapted to be associated with means for causing an electric current to flow along the said jet and means for breaking the said jet under the influence of an electric signal.

25 The means for causing an electric current to flow along the jet may also constitute the means for breaking the jet under the influence of an electric signal; thus the electric signal may consist of a large impulsive current passed through the jet which is broken before the impulse terminates.

30 If a sufficient current is passing through the jet and the jet is broken, an arc will start in the gap or gaps formed; if the voltage between the said electrode and the source is sufficient, the arc 35 will eventually terminate on the said electrode. The said electrode is preferably the cathode or a porous tungsten block partially immersed in the cathode and providing in known manner a fixed surface saturated with the mercury. Then a 40 cathode spot will be formed on the cathode and, if the voltage between cathode and anode is sufficient, the main discharge will start. But the said electrode might be an electrode so near the cathode that an arc formed between the parts of 45 the broken jet transfers itself to the cathode; but no advantage of this alternative is known.

The jet may be broken by simply passing a sufficient current through it; thus I have found that if, for example, the diameter of the jet is 50 some 0.3 mm., a current of 25 amp. will be sufficient to break it. The breaking may be due to the "pinch" effect, but is more probably due to a disturbance originating at the orifice on the application of the electric signal. But other means 55 of breaking the jet may be adopted. Thus the

jet may be permanently subjected to a transverse magnetic field and broken by the lateral force due to a current through it; the current caused to flow along the jet may then be the electrical signal. Conversely, a constant current may be passed along it, and a transverse magnetic field established at the appropriate point in the cycle. Other methods will occur to those skilled in the art.

10 I am aware that it has been proposed to ignite a mercury arc converter (but not necessarily so as to control the starting of the arc in each cycle) by means of a "mercury bridge" broken by the "pinch effect;" but I am not aware that it has been proposed to do so when the "bridge" is a 15 jet. I am aware also that it has been proposed to use mercury jets in various ways to control the ignition of a mercury arc converter; but I am not aware that it has been proposed to do so when the jet flows continuously except when the 20 main discharge is being started, and is broken under the influence of an electric signal when carrying current.

25 The speed of the jet must be such that the jet is renewed in the interval between successive interruptions. If the frequency of the A. C. is 50 cycles, if the jet is interrupted only once per cycle, if the length of the jet is 1 cm. and its diameter 0.3 mm., this condition can be obtained if the head driving the jet is at most a few cm. of 30 mercury.

35 The supply of mercury in the source may be renewed, in steel tank converters, by mercury condensing on the upper part of the tank and led into a container constituting the source. But a pump may be provided, for example the known "3-phase pump" operating by eddy-currents or a piston pump operating similarly to the well-known petrol pump of an automobile. If D. C. is required to be passed through the jet, the impedance of the pumping circuit may be made sufficiently large by including in it a sufficient length 40 of narrow glass tubing.

45 Four embodiments of the invention will now be described, by way of example, with reference to Figures 1, 2, 3 and 4 of the accompanying drawing, of which Figure 1 shows a section through a steel tank converter in accordance with the invention in which mercury is supplied from the cathode pool to a reservoir within the tank by 50 evaporation and condensation and Figures 2, 3 and 4 show steel tank converters in which the mercury issuing in the jet is pumped from the cathode pool.

In Figures 1 and 2 the jet is adapted to be 55

broken under the influence of an impulsive current passed through the jet, and in Figures 3 and 4 the jet is adapted to be broken under the influence of a magnetic field.

- 5 In all the figures 1 is the steel envelope, 2 the anode within it, 3 the cathode pool at the bottom. Mercury flows through the tube 7 and issues from the orifice 8 in the jet 9. Between the anode 2 and cathode 3 is connected the main circuit which 10 is supplied with alternating current from an A. C. source 14 through a transformer 15 and comprises a D. C. load 15. 16 is the source of electric signals which is connected across the primary 10 of a transformer having a secondary 12.
- 15 In Figure 1, 4 is a channel on the envelope 1 collecting mercury condensing on the upper part and 5 a tube through which the condensed mercury drips into a container 6. The container 6 is supported from the wall by an insulating member 11 and is connected to the cathode through the aforesaid secondary 12. Impulsive electric signals from the source 16 are applied to the primary 10 and cause a sufficient current to pass through the jet to break it whilst the current is 20 still passing; the breaking of the current then starts an arc which produces a cathode spot and initiates the discharge between the anode 2 and cathode 3.

25 In Figure 2 the mercury for the jet is pumped into the tube 7 from the cathode 3 by means of a tube 17, communicating with the cathode, and a pump 18.

30 The arrangement of Figure 3 is generally similar to that of Figure 2, but the envelope 1 contains in addition a permanent magnet 19 supported from the wall of the tank by a member 20 and arranged with its pole pieces close to the jet. When current is passed through the jet by means of signals applied from the source 16, the jet is 35 broken under the influence of the transverse force arising from the presence of the magnetic field.

35 In Figure 4 the pole pieces of an electro-magnet 21 are sealed through the lower part of the envelope 1 and arranged about the jet 9; the exciting windings 22 of the magnet are connected in series with the secondary 12 so that the electric signals from the source 16 produce transient magnetic fields between the pole pieces. A D. C. current is passed through the jet by means of a D. C. source 23 so that at each signal from the source 16 the resulting magnetic field produces a lateral force on the jet which suffices to break it and thereby initiate the main anode-cathode 40 discharge.

45 I claim:

1. In a mercury arc converter of the type wherein a discharge occurs within a discharge envelope along an arc from an anode to a mercury pool cathode, means for initiating said discharge, said means comprising means for causing a stream of mercury to issue from an orifice as a continuous jet impinging on an electrode within the discharge envelope, means for causing an electric current to flow along said jet and means for breaking said jet under the influence of an electric signal while the jet current is flowing.

2. In a mercury arc converter of the type wherein a discharge occurs within a discharge envelope along an arc from an anode to a mercury pool cathode, means for initiating said discharge, said means comprising means for causing a stream of mercury to issue from an orifice as a continuous jet impinging on an electrode within the discharge envelope, means for causing an elec-

5 tric current to flow along said jet and means for breaking said jet while said jet current is flowing under the influence of an electric signal during successive cycles of the alternating current rectified by said converter so as to initiate a said discharge in each of said cycles.

3. In a mercury arc converter of the type wherein a discharge occurs within a discharge envelope along an arc from an anode to a mercury pool cathode, means for initiating said discharge, 10 said means comprising means for causing a stream of mercury to issue from an orifice as a continuous jet impinging on an electrode within the discharge envelope, and means for passing a large impulsive current through said jet during successive cycles of the alternating current rectified by said converter so as to break said jet while said impulsive jet current is flowing and thereby initiate the discharge between the said anode and said cathode of said device in each of said cycles. 15

4. In a mercury arc converter of the type wherein a discharge occurs within a discharge envelope along an arc from an anode to a mercury pool cathode, means for initiating said discharge, 20 said means comprising means for causing a stream of mercury to issue from an orifice as a continuous jet impinging on an electrode within the discharge envelope, means for passing an electric current through said jet and means for establishing a magnetic field transverse to the said jet 25 during successive cycles of the alternating current rectified by said converter so as to break said jet, while said jet current is flowing, and thereby initiate a said discharge in each of said cycles.

5. In a mercury arc converter of the type wherein a discharge occurs within a discharge envelope along an arc from an anode to a mercury pool cathode, means for initiating said discharge, 30 said means comprising means for causing a stream of mercury to issue from an orifice as a continuous jet impinging on an electrode within the discharge envelope, means for establishing a constant magnetic field transverse to said jet and means for passing an electric current through 35 said jet during successive cycles of the alternating current rectified by said converter so as to break the said jet, while said jet current is flowing, and thereby initiate a said discharge in each of said cycles. 40

6. In a mercury arc converter of the type wherein a discharge occurs within a discharge envelope along an arc from an anode to a mercury pool cathode, means for initiating said discharge, 45 said means comprising pumping means for pumping mercury from said cathode and causing it to issue from an orifice as a continuous jet impinging on an electrode within the discharge envelope, means for causing an electric current to flow along the said jet and means for breaking said jet while said jet current is flowing under the influence of an electric signal during successive cycles of the alternating current rectified by said converter so as to initiate a said discharge in each of said cycles. 50

7. In a mercury arc converter of the type wherein a discharge occurs within a discharge envelope along an arc from an anode to a mercury pool cathode, means for initiating said discharge, 55 said means comprising a reservoir containing mercury and communicating with an orifice from which a stream of mercury issues under the influence of gravity in the form of a continuous jet impinging on an electrode and falling into the 60

cathode pool, means for leading mercury evaporated from the cathode pool and condensed on the upper part of the said discharge envelope in operation into the said reservoir, means for causing an electric current to flow along said jet and means for breaking said jet, while said jet current is flowing, under the influence of an electric signal during successive cycles of the alternating current rectified by said converter so as to initiate a said discharge in each of said cycles.

8. In a mercury arc converter of the type wherein a discharge occurs along an arc from an anode to a mercury pool cathode, means for initiating said discharge, said means comprising means for causing a stream of mercury to issue from an orifice in the form of a continuous jet falling into said cathode pool, means for causing an electric current to flow along said jet and means for breaking said jet, while said jet current is flowing, under the influence of an electric signal during successive cycles of the alternating current rectified by said converter so as to initiate a said discharge in each of said cycles.

9. In a mercury arc converter of the type wherein a discharge occurs at regular temporal intervals along an arc from an anode to a mercury pool cathode, means for initiating said discharge at each of said intervals, said means comprising an orifice, means for causing a jet of mercury to issue continuously from said orifice, means for causing an electric current to flow along said jet and means for breaking said jet at each of said intervals while said jet current is flowing. 10

10. In a mercury arc converter of the type wherein a discharge occurs at regular temporal intervals along an arc from an anode to a mercury pool cathode, means for initiating said discharge at each of said intervals, said means comprising an orifice spaced apart from said cathode pool, means for causing a jet of mercury to issue continuously from said orifice and impinge said cathode pool, means for causing an auxiliary electric current to flow along said jet and means for breaking said jet at each of said intervals while said jet current is flowing. 15 20
